UNITED STATES PATENT OFFICE.

ROBERT L. PARSONS, OF OAKVILLE, KENTUCKY.

CHECK-ROW CORN-PLANTER.

SPECIFICATION forming part of Letters Patent No. 737,134, dated August 25, 1903.

Application filed March 30, 1903. Serial No. 150,220. (No model.)

To all whom it may concern:

Be it known that I, ROBERT L. PARSONS, a citizen of the United States, residing at Oakville, in the county of Logan and State of Kentucky, have invented a new and useful Check-Row Corn-Planter, of which the following is a specification.

This invention relates to check-row corn-planters.

10 The object of the invention is to provide an improved construction of marking mechanism operated by the wheels of the planter and adapted to be disconnected by the driver without leaving his seat and to be readily adjusted in position, so that the hills may be laid off in parallel lines in both directions of the field.

To this end the invention consists in the construction and combination of parts of a 20 check-row corn-planter hereinafter fully described, illustrated in the accompanying drawings, forming a part of this specification, in which corresponding parts are designated by the same characters of reference throughout the various views in which they appear, and having the novel features thereof specifically pointed out in the appended claims.

In the drawings, Figure 1 is a view in side elevation of a corn-planter constructed in accordance with my invention. Fig. 2 is a view of the corn-planter from above with the driver's seat removed to show the structures lying beneath it. Fig. 3 is a detail view in elevation of a marker and the mechanism for securing it to a wheel, a portion of the wheel being shown in connection therewith. Fig. 4 is a detail view in vertical section through a wheel in the plane of its axle, showing a marker and the associated mechanism attached to the 35 wheel. Fig. 5 is a transverse section through one of the corn-hoppers, part of the bottom being broken away to show the dropping mechanism beneath. Fig. 6 is a vertical section through the lower portion of one of the corn-hoppers and dropping devices below it.

40 Referring to the drawings, 1 designates the frame of the planter, which is of the usual form, comprising side pieces 2 and end pieces 3 and having a central cross-brace 4 supporting the forward ends of two longitudinally disposed bars 5, the rear ends of which are attached to the rear frame member of the

planter. The frame 1 is supported on an axle 6 by means of supporting brackets 7, provided at their lower ends with journals 8 for the axle. 55 Rotatably mounted on the axle, at either end thereof, is a wheel 9 of the usual construction, comprising a hub 10, spokes 11, and a felly 12 and having secured to the spokes by means of clamps 13 and projecting lugs 14 an annular rack 15, provided with a plurality of radially-disposed oblong openings 16, spaced equidistant throughout the entire circumference of the rack.

On the axle 6, at a point adjacent the inner 65 end of the hub of each of the wheels, there is provided a squared portion 17 and at the inner side of said squared portion an annular shoulder 18, the squared portion and annular shoulder forming a seat for a marker-bar 19 of a length slightly greater than the diameter of each of the wheels and provided at the middle with a square socket adapted to fit the squared portion 17 on the axle. Extending through the marker 19, at suitable 70 points near either end, are locking-bolts 20, the operative ends of which are of a shape to correspond to the oblong sockets provided in the annular rack carried by each of the wheels. The locking-bolts pass through the 75 marker-arms at points such that when the locking-bolts are turned so that the operative ends are placed in the position shown in Fig. 4 they will pass through openings in the annular rack and lock the marker securely to 80 the wheel; but when the locking-bolts are withdrawn from engagement with the rack and given a quarter-turn in their bearings in the marker-bar they can no longer enter the 85 openings in the rack, and the marker-bar and wheels may be moved independently of each other.

The locking-bolts 20 pass through openings provided in the pivoted levers 21, each of which is mounted in a bracket 22 on the 95 marker-arm 19, near the axle of the planter, and has a forked inner end 23, adapted, as shown in Fig. 3, to embrace the axle without coming into contact therewith. The forked ends of the pivoted levers 21 of each marker-bar are of slightly different sizes, so that they may be pivotally connected, as shown in Fig. 3. At their outer ends pivoted levers 21 are connected with the marker-bar by means of

contractile springs 24, which normally draw the outer ends of the levers 21 toward the marker. The locking-bolts 20, which pass through the openings in the outer ends of the 5 pivoted levers 21, are rotatable in said openings, but are not slideable therein, so that the movement of the locking-bolts when drawn out of engagement with the annular rack 16 is communicated to the outer ends of the 10 pivoted levers 21, causing said ends to be forced away from the marker-bar against the tension of springs 24, and vice versa. Consequently when the locking-bolt at one end of a marker-bar is drawn out of engagement 15 with the rack 16 the end of the lever 21 in which said bolt is mounted will be forced outward, and the outer end of the other lever 21, which is pivotally connected with that one which carries the locking-bolt which is drawn 20 out of engagement, will also be forced outward, withdrawing the locking-bolt carried by it from engagement with the rack 16. By this arrangement it is obvious that when it is desired to disengage the locking-bolts 25 on a marker from the sockets in the rack 16 it is not necessary to withdraw each locking-bolt separately, but the withdrawal of either will cause the withdrawal of the other through the action of the pivoted levers 21.

30 When a locking-bolt has been withdrawn from engagement with the rack 16, it may be turned, as stated in a preceding paragraph, through an angle of ninety degrees, and the operative end of the locking-bolt, which is of 35 configuration similar to that of the sockets provided in the rack, will no longer enter any of these sockets, but will be disposed transversely thereto and will press against the rack-bar without entering into locking engagement therewith. To facilitate the withdrawal of the locking-bolts and their rotation in the bearings provided in the marker-bar and pivoted levers 21, each of the bolts is provided at its inoperative end with a ring 25 40 or other means for obtaining a hold thereon.

At the forward end of the frame 1 is provided a transversely-disposed plate 26, provided at either end with a corn-hopper 27 of ordinary construction, having an opening 28 50 in the bottom thereof, as shown in Fig. 5, and having a rotary disk 29, provided with a plurality of openings 30, mounted on a pivot 31, which extends downward through the bottom of the hopper and the transverse plate 26. 55 Attached to the under side of each end of the plate 26 is a runner or furrow-opener 32 of the usual construction, the rear portion of which has a channel 33 for the passage of the corn, which is dropped through an opening 60 34 in the plate 26 above the said channel.

The disk 29 is provided with a plurality of rotary arms 35, extending radially from its periphery, as shown in Fig. 2, each arm corresponding to one of the openings 30, which 65 extend through the disk.

In order to impart rotation to the disks 29 under hoppers 27, I provide a shaft 36 in bear-

ings formed in the upper portion of standards 37, mounted on the transverse plate 26 and having at either end a tappet-arm 38, which 70 engages with one of the radial arms 35 at each half-revolution of the shaft 36. Motion is imparted to the shaft 36 by means of a sprocket 39 on the shaft 36, a sprocket 40 on the axle of the planter, and a sprocket-chain 41, which 75 passes over the two sprockets, as shown in Figs. 1 and 2.

In order to insure proper contact of the runners 32 with the ground, the frame 1 of the planter is connected with the tongue 42 by 80 means of a bracket 43 and pivot 44 at the forward end of the frame, and adjusting mechanism is provided at the rear portion of the frame convenient to the driver's seat, as will be presently described, and in order to prevent any lateral movement of the tongue relative to the frame of the planter there is mounted at the rear end of the tongue a segmental bearing 46, which is secured in position by bolts, as shown in Fig. 1, and passes 90 upward through a guideway 47 at the rear of the frame immediately under the driver's seat 48.

The means for adjusting the position of the frame relative to the tongue comprises a short 95 shaft 49, journaled in bearings on the longitudinal members 5 and having rigidly secured to it at the middle an arm 50, the free end of which is connected by a link 51 with the tongue. At one end of the shaft 49 is rigidly 100 mounted an operating-lever 52, provided with a spring-pressed locking-bolt 53, having releasing devices of the usual form and adapted to engage a segmental rack 54, provided on the upper surface of the adjacent longitudinal member 5.

By means of the lever 52, the rock-shaft 49, and arm 50 it will be readily seen that the rear portion of the frame 1 of the planter may be raised or lowered at will in order to bring 110 the proper portion of the runners 32 into contact with the ground.

In operation the corn-hoppers are filled with corn, the marker-arm on one of the wheels is locked in engagement therewith, and the machine driven across the field in any direction desired. The rotation of the wheel to which the marker-arm is locked will impart movement to the axle, and this in turn will drive the mechanism by means of which the disks 115 at the bottom of the corn-hoppers are rotated, causing the corn to be dropped in predetermined quantities at regular intervals across the field in two rows separated by a distance 120 equal to the width of the planter. When the trip across the field has been completed, the driver will release the marker-arm from engagement with the rack on the wheel by withdrawing the locking-bolt, which is most easily 125 reached from his seat, and will turn the locking-bolt sufficiently to prevent it from re-entering one of the sockets provided in the rack. This will allow the wheels to rotate independently of the axle and will permit the machine 130

to be turned without causing the operation of the corn-dropping apparatus. When the machine has been turned for the return trip, the marker-bar attached to the wheel which lies nearest the rows already planted will be adjusted in position to align the hills in the two rows about to be planted, and the machine will be driven across the field in the direction opposite to that first traveled. This course of procedure is followed until the whole field has been planted.

As the operation of the disks at the bottom of the corn-hoppers is well known in the art and I do not claim the same as my invention, a detailed account of the operation thereof is regarded as unnecessary.

It is of course obvious that changes may be made in the form, proportions, and exact mode of assemblage of the elements described in the preceding paragraphs and shown in the accompanying drawings without departing from the spirit of the invention, and I do not wish to be limited to the exact construction shown and described, but reserve the right to make such changes therein as do not depart from the spirit of the invention or sacrifice any of its advantages.

Having thus described the construction and operation of my invention, what I claim as new, and desire to secure by Letters Patent, is—

1. The combination in a check-row corn-planter of an axle, wheels rotatable on said axle, a marker rigidly mounted on said axle adjacent to each of said wheels, an annular rack mounted on each of said wheels and provided with a plurality of radially-disposed oblong openings, a locking-bolt carried by each of said markers and having an end adapted to fit openings in said rack and being susceptible of partial rotation to throw it out of registration with said openings.

2. The combination in a check-row corn-planter of an axle, wheels rotatably mounted on said axle, an annular rack secured to each wheel, a marker-bar rigidly mounted on said axle adjacent to each of said wheels, a rack

carried by each of said wheels, a pair of pivoted levers mounted on each marker and pivotally connected at their inner ends, springs connecting the free ends of said levers with said marker and tending to draw said lever ends toward said marker, and locking-bolts carried by said levers and adapted to engage the racks mounted on said wheels.

3. The combination in a check-row corn-planter of an axle, wheels rotatably mounted on said axle, an annular rack secured to each wheel, a marker rigidly mounted on said axle adjacent to each of said wheels, a pair of pivoted levers mounted on each of said markers and having their adjacent ends pivotally connected, springs connecting the distal ends of said levers with said marker, and locking-bolts rotatably mounted in the distal ends of said levers and adapted to engage said racks.

4. The combination in a check-row corn-planter of an axle, an annular rack carried by each of said wheels, a marker rigidly mounted on said axle adjacent to each of said wheels, a pair of pivoted levers mounted on said marker the inner ends of said levers being formed to embrace said axle and being pivotally connected, and locking-bolts mounted in the outer ends of said levers and adapted to engage with said rack.

5. The combination in a check-row corn-planter of an axle, wheels rotatably mounted on said axle, an annular rack provided on each of said wheels, a marker rigidly mounted on said axle adjacent to each wheel, a spring-pressed locking-bolt on each of said markers and adapted to engage said annular rack, and means provided on each of said bolts for withdrawing it from engagement with said rack and locking it in disengaged position.

In testimony that I claim the foregoing as my own I have hereto affixed my signature in the presence of two witnesses.

ROBERT L. PARSONS.
